UNITED STATES PATENT OFFICE.

JOSEPH H. KNAUS, OF FAYETTE, MISSOURI, ASSIGNOR OF TWO-THIRDS TO
WALTER C. KNAUS AND LEWIS L. LYNN, BOTH OF SAME PLACE.

DRAWER.

SPECIFICATION forming part of Letters Patent No. 363,647, dated May 24, 1887.

Application filed March 19, 1887. Serial No. 231,600. (No model.)

To all whom it may concern:

Be it known that I, JOSEPH H. KNAUS, a citizen of the United States, residing at Fayette, in the county of Howard and State of Missouri, have invented certain new and useful Improvements in Attachments for Drawers, of which the following is a specification, reference being had to the accompanying drawings, forming part thereof, in which—

10 Fig. 1 is a plan view of the attachment, the drawer and the casing in which it moves being shown in dotted lines. Fig. 2 is a perspective view from the rear of the case, the drawer being partly withdrawn and the top of the case being removed. Fig. 3 is a diagram showing a modification.

The object of my invention is to provide an equalizing attachment for drawers, whereby the binding of the drawer in moving it in and out of its casing will be prevented and the friction incident thereto obviated.

The invention will be first described, and then specifically pointed out in the claims.

15 A represents the casing, which may be in the form of a bureau or other article, having an opening, into and out of which the drawer B may slide. The back of the casing is apertured to receive the two horizontal pulleys C C, mounted in U-shaped brackets D D, provided with apertured ears d d, which are secured to the rear side of the casing A at opposite sides of the apertures by means of screws d' d'. The front of the casing is provided with horizontal pulleys E E in the plane of the pulleys C C. The pulleys E E are journaled in brackets E' E', secured to the under side of the cross-piece A' at the top of the drawer-opening by means of screws passing through the apertured ears e e, projecting from the ends 20 of the said brackets. Around these four pulleys passes an endless flexible strand, F, which is crossed at f, thus forming the parallel ends f' f' and the crossed diagonal portions f'' f''. To each of the ends f' f' is secured an angular 25 attaching-arm, G, the horizontal branch g of which has at its opposite sides one or more projections, g', which are bent over the strand to secure the arm thereon. The vertical branches g'' of the arms G project downward

and into the open spaces H' behind the cleats 50 H, secured, preferably, to the inner face of the back of the drawer B at or near its upper edge. The arms G may be readily detached from the cleats by simply moving their vertical branches g'' sidewise, when the drawer may be removed 55 from its casing.

By this construction it will be seen that the force applied in opening and closing the drawer will be equalized—that is, applied equally to both sides—so that the drawer will move only 60 in a straight line, and sidewise or jerky movement and consequent binding be prevented. The lower ends of the branches g'' are bent outward slightly, in order that they may be readily grasped when it is desired to disconnect the arms G from the drawer. In Fig. 3 the same arrangement of the pulleys and connecting-arms is employed; but the endless strand G is doubled and passed around a rear pulley, thence to and around the forward pulleys, and back to and around the other rear pulley.

The strand may be formed of cord, wire, or chain, as desired, and any suitable form of pulley may be used. The strand may be permanently connected at its sides to the rear upper corners of the drawer, if found desirable; but I prefer a readily-detachable connection.

Having thus described my invention, what I 80 claim as new, and desire to secure by Letters Patent, is—

1. The combination, with the casing and the drawer, and pulleys at the front and rear of the casing at opposite sides of the drawer-opening, of the endless strand passing around the said pulleys and connected to the rear end of the drawer at or near its opposite ends, substantially as set forth.

2. The combination, with the casing and its drawer, of the pulleys at the front and rear of the casing, and the endless crossed strand passing around said pulleys and connected at its sides to the drawer, substantially as set forth.

3. The combination, with the casing and its drawer, of the pulleys at the front and rear of the casing at opposite sides of the drawer-opening, and the endless strand passing around

said pulleys, as described, and removably connected at its sides to the drawer, substantially as set forth.

4. The combination, with the casing and its drawer having cleats, of the pulleys at the front and rear of the casing at opposite sides of its drawer-opening, and the endless strand passing around the pulleys and having the depending arms entering the spaces in rear of the cleats, substantially as set forth.

5. In a drawer-equalizing attachment, the angular connecting-arm formed with clamping projections on its horizontal arms, whereby it may be readily secured to a strand, substantially as set forth.

JOSEPH H. KNAUS.
